J. GOULBOURN,
FASTENER SETTING MACHINE,
APPLICATION FILED AUG. 5, 1918.

1,401,251.

Patented Dec. 27, 1921.

INVENTOR.
Joseph Gouldbourn
By his Attorney,
Nelson Howard

UNITED STATES PATENT OFFICE.

JOSEPH GOULDBOURN, OF LEICESTER, ENGLAND, ASSIGNOR TO UNITED SHOE MACHINERY CORPORATION, OF PATERSON, NEW JERSEY, A CORPORATION OF NEW JERSEY.

FASTENER-SETTING MACHINE.

1,401,251.

Specification of Letters Patent. Patented Dec. 27, 1921.

Application filed August 5, 1918. Serial No. 248,344.

To all whom it may concern:

Be it known that I, JOSEPH GOULDBOURN, a subject of the King of England, and resident of Leicester, Leicestershire, England, have invented certain Improvements in Fastener-Setting Machines, of which the following description, in connection with the accompanying drawings, is a specification, like reference characters on the drawings indicating like parts in the several figures.

This invention relates to fastener-setting machines, and more especially to machines having automatic mechanism for supplying fasteners to the setting mechanism, and having mechanism for feeding the work step by step.

An object of the invention is to provide improved controlling means adapted to control both the fastener-supplying mechanism and the work-feeding mechanism, either collectively or individually, as the case may be. For purposes of illustration the invention is herein disclosed as being embodied in an eyeleting machine of which the eyelet-supplying mechanism may be rendered inoperative temporarily, and of which the work-feeding mechanism may be altered to increase or to decrease the length of the steps. In some cases it is desirable to stop the supplying of eyelets while the machine continues to punch holes in and to feed the work with or without a change in the length of the feeding steps. On the other hand it is sometimes desirable to change the length of the feeding steps without discontinuing the supplying of eyelets. The invention therefore provides for satisfying the various conditions above mentioned.

More specifically an object of the invention is to provide controlling means for the purposes stated, in a machine having work-feeding mechanism of the type disclosed in Letters Patent of the United States No. 683,488 granted October 1, 1901 on an application of M. H. Pearson. I am aware that it has been proposed to provide controlling means having a corresponding dual function in a machine comprising another type of work-feeding mechanism, for example that disclosed in Letters Patent of the United States No. 1,048,836 granted December 31, 1912 on an application of A. E. Jerram, but the controlling means shown in the latter patent would not be suitable for a machine having work-feeding

mechanism of the type shown in the aforesaid Pearson patent.

The invention will be best understood from a consideration of the following specification taken in connection with the accompanying drawing, in which,—

Figure 1 is a front elevation of a machine embodying the present invention;

Fig. 2 is a plan view partly in section of the right hand end of the machine and 65 shows the control mechanism;

Fig. 3 is a diagrammatic view showing the spacing mechanism; and

Fig. 4 is a view of the treadle controlled member.

Reference may be had to the above-mentioned Jerram Patent No. 1,048,836 for a description of parts not herein fully described but in general such a machine will comprise a punch 10, setting devices 12, a 75 hopper 14, and a raceway 16. Movement of the various parts is effected from a power operated shaft 18.

The delivery of fasteners to the setting devices is effected by means of a spindle 20 80 frictionally mounted within the upper set 12 (see Fig. 6 of the Jerram patent) and adapted to be projected through the end-most eyelet in the raceway 16 by means of a finger 22 (see Fig. 2). It will be noted 85 that the end of this finger 22 which projects within the set 12 is beveled at its upper side in order that no harm may result in case the finger is projected into the set at the time the spindle 20 is in elevated position, but the finger 22 will be pushed aside against the action of a treadle spring 72 to be later described. Locking means comprising a sliding pin 24 and an eccentric 26, operated by means of a handle 28, are provided for securing the finger 22 in its operative position, that is to say, in the position in which it will expel the spindle 20 during the retraction of the set. A lever 30 having a pin and slot connection with the 100 finger 22 and loosely pivoted upon a vertical shaft 32 journaled in a bracket 33 on the machine frame, is provided at one end with a member 34 provided with teeth arranged concentric with the shaft 32 and 105 for a purpose to be later described.

As in the arrangement of the Jerram patent, the spacing of the eyelets is secured by feeding the work by means of a lateral movement of a punch lever 40 carrying the 110

punch 10. This lever 40 is mounted for vertical movement within a frame 42 which is pivotally mounted at 44 for lateral movement about a pivotal axis. According to 5 the present invention, this lateral movement is effected by transmitting the movement of a lever 46, pivoted at 47 and operated from a cam 47', through two pivotally connected links 48. As in the arrangement of the 10 Pearson patent, the path of movement of the connecting point between said links is controlled by means of a link 50 which is mounted on a pivot stud 52 carried by an arm 54 fixed on the shaft 32 and having a 15 toothed portion in the same plane as the toothed portion 34 of the lever 30. The length of the link 50 is equal to the distance between the centers of the pivot 52 and the shaft 32. Manual movement of the arm 54 20 to vary the position of the stud 52 is secured by means of a handle 56 pinned to the upper end of the shaft 32 and movable over a perforated plate 58 into which pins 60 may be inserted for limiting the movement 25 of the handle 56. The toothed portion of the arm 54 is also concentric with the shaft 32.

Interposed between the toothed portion 30 of the arm 54 and the toothed portion 34 is a pinion 62 meshing with said toothed portions and supported for rotation within the forked end 64 of a rearwardly extending rod 66. This rod is adapted to be manually actuated in one direction through a 35 bell crank lever 68 by means of a rod 70 connected to a treadle or other suitable device (not shown) and in the other direction by a spring 72.

If neither the finger 22 nor the handle 40 56 is locked in position, the operator, without losing control of the work and while the machine is in operation, may by depressing the treadle cause the forward movement of the pinion 62 to shift both the 45 toothed arm 54 of the spacing mechanism and the toothed portion 34 of the eyelet controlling mechanism so as simultaneously to increase the spacing between the punched holes and at the same time to withdraw the 50 finger 22 to prevent the ejection of the spindle 20 and hence to prevent the delivery of eyelets to the setting mechanism. If, however, either one of these toothed arms is locked in position or reaches its limiting 55 position before the other, the pinion 62 will roll upon the locked arm and cause movement of the other arm thereby to control that mechanism which is unlocked. Upon release of the treadle, the spring 72 60 will cause retraction of the pinion 62 and reverse the operation.

It will be understood that, although the invention has been illustrated and described in connection with a particular machine and 65 particular control mechanisms, its use is not

so limited and it can be applied to other similar machines to effect similar results.

Having thus described my invention, what I claim as new and desire to secure by Letters Patent of the United States is:

1. A fastener-setting machine comprising fastener-supplying mechanism including a pivoted member arranged to render said mechanism operative and inoperative, work-feeding means including a pivoted member arranged to vary the length of the feeding steps, adjustable means adapted to control the functioning movement of one of said pivoted members, and means arranged to impart functioning movement to one of said pivoted members or to both collectively, as may be determined by said adjustable means.

2. In a machine of the character described, control elements provided with toothed portions and arranged to execute controlling movement collectively or independently of each other, as the case may be, a pinion interposed between and engaging the toothed portions of said members, means to move said pinion so as to move one or both of said control elements, and means usable at will for restraining one of said control elements from moving under stress of said pinion.

3. In a machine of the character described, pivoted levers provided with toothed portions arranged in juxtaposition, a pinion interposed between said toothed portions, means for locking one of said control levers in predetermined position, and means for moving said pinion to move the unlocked control lever while rolling in engagement with the toothed portion of the locked lever.

4. In a fastener setting machine, setting means comprising a frictionally positioned spindle adapted to be projected from and retracted within said setting means, means for controlling the projection of said spindle including a pivotally mounted member, means for locking said spindle controlling means in one position, work feeding means comprising a pair of pivotally connected links, means for controlling the path of movement of the point of connection of said links comprising a pivoted member, means for locking said pivoted member in a predetermined position, means for connecting said pivoted members, and manually operated means for moving said connecting means so as to move one or both of said controlling members according as one or both of them are free to move.

5. In a machine for operating on boots and shoes, in combination, work-feeding mechanism including compounded links arranged to co-act in various relationships so as to vary the feeding action, two controlling elements one of which is arranged to vary the relationship of said links and the other

of which controls the machine in another respect, an actuator, means operable by said actuator to impart effective movement to one or both of said controlling elements 5 according to whether one or both of them are free to move, and means usable at will for restraining one of said controlling elements.

6. A fastener-setting machine comprising 10 control elements arranged to move conjointly and severally, said elements having toothed portions, a bodily movable and rotatable member having means constructed and arranged to co-act with said toothed portions 15 of the control elements, adjustable means arranged to control the functioning of one of said control elements, and manually operable means arranged to shift said rotatable member bodily so as to move one or both of 20 said control elements as one or both of them are free to move.

7. A machine comprising setting tools, means for delivering eyelets to the setting tools, means for controlling the eyelet delivering means, work feeding means including pivotally connected links, means for controlling the spacing effected by said work feeding means comprising means for controlling the path of movement of the point 30 of connection of said links, manually operable mechanism interposed between the means for controlling the delivery of eyelets and the means for controlling the spacing of the eyelets and arranged to move one or both 35 of the controlling means according as one or both of them are free to move, and means usable at will to limit or prevent effective movement of one of said controlling means.

8. In a machine for operating on boots and 40 shoes, the combination with mechanism for supplying fasteners, mechanism for feeding the work, and independently movable controllers for controlling said mechanisms respectively, of means arranged to move the 45 controllers simultaneously in a common direction and to move one of them if the other one is restrained against moving, and means usable at will to prevent or limit effective movement of one of said controllers.

50 9. In a machine for operating on boots and shoes, the combination with mechanism for supplying fasteners, and mechanism for feeding the work, of two controllers for controlling said mechanisms respectively, each 55 of said controllers being movable about an axis independently of the other, means arranged to impart angular movement to said controllers simultaneously and to one of

them if the other one is restrained against angular movement, and means usable at will 60 to prevent or limit effective movement of one of said controllers.

10. In a machine for operating on boots and shoes, the combination with mechanism for supplying fasteners, and mechanism for feeding the work, of two controllers movable about a common axis independently of each other for controlling said mechanisms respectively, means arranged to move said controllers collectively about said axis and to 70 move one of them if the other one is restrained against such movement, and means usable at will to prevent or limit effective movement of one of said controllers.

11. In a machine for operating on boots 75 and shoes, the combination with mechanism for supplying fasteners, mechanism for feeding the work, and independently movable controllers for controlling said mechanisms respectively, of toothed gearing arranged to move said controllers simultaneously and to move one of them if the other one is restrained against movement, and means usable at will to prevent or limit effective movement 80 of one of said controllers.

12. In a machine for operating on boots and shoes, the combination with mechanism for supplying fasteners, mechanism for feeding the work, and independently movable controllers for controlling said mechanisms 90 respectively, of toothed gear-members associated with said controllers respectively, means including a toothed gear arranged to co-act with both said gear-members to move said controllers simultaneously and to move 95 one of the latter if the other one is restrained, and means usable at will to prevent or limit effective movement of one of said controllers.

13. In a machine for operating on boots 100 and shoes, the combination with mechanism for supplying fasteners, and mechanism for feeding the work, of two controllers movable about an axis independently of each other for controlling said mechanisms respectively, a bodily movable and rotatable toothed gear, toothed segments meshed therewith and arranged to transmit motion of said gear to said controllers simultaneously and to one of the latter if the other one is restrained, means for moving said gear bodily, and means usable at will to prevent or limit effective movement of one of said controllers. 105

In testimony whereof I have signed my name to this specification.

JOSEPH GOULBOURN.
